UNITED STATES PATENT OFFICE

HARRY CROSSMAN, OF BROOKLINE, ARTHUR GREENBAUM, OF BEACHMONT, AND MAURICE J. BERNSTEIN, OF BROOKLINE, MASSACHUSETTS, ASSIGNEES TO PANTHER RUBBER MANUFACTURING COMPANY, OF STOUGHTON, MASSACHUSETTS, A CORPORATION OF MASSACHUSETTS

DESIGN FOR A SHOE HEEL

Application filed November 29, 1930. Serial No. 37,841. Term of patent 14 years.

To all whom it may concern:

Be it known that we, HARRY CROSSMAN, ARTHUR GREENBAUM, and MAURICE J. BERNSTEIN, citizens of the United States, residing, respectively, at Brookline, county of Norfolk, Beachmont, county of Suffolk, and Brookline, county of Norfolk, Commonwealth of Massachusetts, have invented a new, original, and ornamental Design for a Shoe Heel, of which the following is a specification, reference being had to the accompanying drawing forming a part thereof.

In the drawing, Fig. 1 is a plan view of a heel, showing our new design; Fig. 2 is a side elevation of a heel; and Fig. 3 is a cross-section on line 3—3, Fig. 1.

We claim:

The ornamental design for a shoe heel as shown.

HARRY CROSSMAN,
ARTHUR GREENBAUM,
MAURICE J. BERNSTEIN.
